UNITED STATES PATENT OFFICE

2,532,003

MEANS FOR USE IN APPLYING, ALTERNATIVELY, AIR PRESSURE AND SUCTION TO A GIVEN POINT

John M. Wyer, Perton, Pattingham, near Wolverhampton, England

Application September 30, 1946, Serial No. 709,222
In Great Britain October 3, 1945

3 Claims. (Cl. 251—96)

1

There are many cases where it is required to apply, alternatively, air pressure or suction at a given point, for instance at a chuck used for retaining a utensil thereon or therein by creating suction within the chuck during some operation on the utensil, and then applying air pressure to the chuck to remove the utensil. The invention has for its object to provide improved means for the above purpose.

The invention comprises a valve constituted by a plug rotatable in an outer shell to which lead two pipes one of which is subjected to air pressure and the other to suction, the shell being closed at one end and having at its other end a passage leading to the point where the pressure or suction is to be alternatively applied, the shell having also a port communicating with the atmosphere. Ports or passages are formed in the plug and are so arranged that, at one position of the plug, the pressure pipe is put in communication with the point of application while the suction pipe is put in communication with the atmosphere so that air can flow back along the suction pipe conveniently to feed an air pump; while, at another position of the plug, the suction pipe is put in communication with the point of application and the pressure pipe in communication with the atmosphere, so that only atmospheric pressure may oppose the pump when acting to create the suction.

A convenient embodiment of the invention is described with reference to the accompanying drawings, of which:

Figure 1 is a longitudinal vertical section of the valve and its carrier the section being taken in the plane indicated by the line 1, 1, of Figure 2.

Figure 2 is an end view of the valve looking in the direction of the arrow of Figure 1.

Figures 3, 4 and 5 are transverse sections each taken in the plane indicated by the line 3, 3, of Figure 1 and showing different positions of the plug.

In these drawings A indicates the shell of the valve mounted in a carrier P and B is the rotatable plug. The shell has a central passage C leading to the point where the pressure or suction is to be alternatively applied. The other or front end of the shell is closed by a gland D out through which passes a forward portion b of the plug having secured to its forward end a wheel E by which it is turned.

The shell A has three main ports disclosed at angles of 90 degrees, one of which F is a pressure port communicating by a pipe F' with the pressure side of an air pump (not shown), an-

2

other of which G is a suction port communicating by a pipe G' with the suction side of the pump and the third of which H is a port communicating with the atmosphere.

5 5. The plug B is closed at its forward end by a wall b' and it is divided by a longitudinal wall b² into two chambers K and M, the chamber K being open at its rear end to the passage C. The chamber M is closed at its rear end by a wall m.

10 10. The chamber K has two peripheral ports k', k², disposed at right angles and the chamber M has two peripheral ports m', m².

15 It will be seen, by reference to Figure 3, that the port k² of the chamber K is in communication with the pressure port F of the shell, the other port k' being closed by the body of the shell. Hence pressure is applied through the chamber K to the passage C. At the same time the port m² of the plug is in communication with 20 the suction port G and the port m', in the plug, with the atmospheric port H in the shell so that air can flow freely to the suction side of the pump.

25 Referring to Figure 4 it will be seen that the port k' of the chamber K is in communication with the port G of the shell so that suction is applied to the passage C through the chamber K. At the same time the port m' of the plug is in communication with the pressure port F of the shell allowing pressure air to flow into the chamber M and out therefrom through the port m² of the plug and the port H of the shell.

30 Referring to Figure 5 the port k² has just commenced to open to the pressure port F but it is also open to an auxiliary port J allowing air to blow out and relieve the point of application of too sudden application of pressure. When the port k² is fully open to the port F the auxiliary port J becomes closed by the space between the ports k' and k².

35 40. The degree of opening the port F can be varied at will and at the same time the degree of blow out by the port J. Hence the degree of pressure applied to the passage C can be controlled. A similar action takes place when the port k' is opening to the suction port G.

45 It is to be understood that the ports referred to as communicating with the atmosphere may communicate with any region where the pressure is substantially that of the atmosphere.

Having fully described my invention what I claim and desire to secure by Letters Patent is:

50 55. 1. A valve for use in applying, alternatively, air pressure and suction to a given point, said valve comprising an outer shell, a plug rotatable

in said outer shell, two pipes leading to said shell, one of which is an air pressure pipe, and the other of which is a suction pipe, said shell being closed at one end, a passage leading from the other end of the said shell to the point where the pressure or suction is to be alternatively applied, a port in said shell communicating with the atmosphere, ports in said plug so arranged that, at one position of the plug, the pressure pipe is put in connection with the point of application while the suction pipe is put in communication with the atmosphere so that air can flow back along the suction pipe; while, at another position of the plug, the suction pipe is put in communication with the point of application and the pressure pipe with the atmosphere and an auxiliary port through said shell open to the atmosphere positioned between said two pipes and arranged to communicate with said ports of said plug when said plug is rotated to a position wherein the ports of said plug begin to communicate with said pressure or suction pipes to prevent a sudden application of pressure or suction to said point.

2. A valve for use in applying, alternatively, air pressure and suction to a given point, said valve comprising an outer shell, two oppositely disposed ports in said shell to which pressure and suction pipes lead respectively, a third port in said shell placed midway between said pressure and suction ports, a plug rotatable in said shell, a longitudinal partition in said plug dividing it into two chambers, each of which is closed at one end and one of which is closed at its other end also, while the other chamber is open at its other end to a passage leading to the point of application, and two angularly disposed ports in the peripheral wall of each said chamber and an auxiliary port through said shell open to the atmosphere positioned between

said oppositely disposed ports and arranged to communicate with said chambers through said angularly disposed ports when said plug is rotated to initial position wherein the chambers communicate with said pressure or suction pipes to prevent a sudden application of pressure or suction to said point.

3. A valve for use in applying, alternatively, air pressure and suction to a given point, said valve comprising an outer shell, two oppositely disposed ports in said shell to which pressure and suction pipes lead respectively, a third port in said shell placed midway between said pressure and suction ports, a plug rotatable in said shell, a longitudinal partition in said plug dividing it into two chambers, each of which is closed at one end and one of which is closed at its other end also, while the other chamber is open at its other end to a passage leading to the point of application, and two angularly disposed ports in the peripheral wall of each said chamber, and a fourth port in said shell communicating with the atmosphere and so placed that, at less than full opening to the pressure pipe, air is allowed to blow out through said fourth port, and at less than full opening to the suction pipe, air is allowed to flow in through said fourth port.
